UNITED STATES PATENT OFFICE.

DAVID B. WEAVER AND EPHRAIM R. HOLSINGER, OF HOPEWELL TOWNSHIP,
HUNTINGDON COUNTY, PENNSYLVANIA.

CURRY-COMB.

SPECIFICATION forming part of Letters Patent No. 248,817, dated October 25, 1881.
Application filed May 26, 1881. (Model.)

To all whom it may concern:

Be it known that we, DAVID B. WEAVER and EPHRAIM R. HOLSINGER, of Hopewell township, in the county of Huntingdon and State 5 of Pennsylvania, have invented a new and valuable Improvement in Curry-Combs; and we do hereby declare that the following is a full, clear, and exact description of the construction and operation of the same, reference 10 being had to the annexed drawings, making a part of this specification, and to the letters and figures of reference marked thereon.

Figure 1 of the drawings is a representation of a sectional view of our invention. Fig. 2 is 15 a top view, and Fig. 3 is a bottom view.

This invention has relation to curry-combs; and it consists in the construction and novel arrangement of the handle extension or rib and its threaded perforations and thumb-screws, 20 the projecting heads of the rivets or bolts under the back plate, and the removable and reversible sections carrying the combs, brushes, or cards, and having elongated tapering or key slots for the rivet or bolt heads, all as herein- 25 after shown and described.

In the accompanying drawings, the letter A designates the back plate, which may be of any ordinary size and form.

B indicates the handle, and C the handle 30 extension or rib, which is applied along the middle line of the back of the plate A and secured thereto, as indicated at *a a*. Threaded perforations *b* are made through this rib to receive the thumb-screws E, which extend 35 through perforations in the back plate, and through perforations *c*, made in the centers of the removable sections D D' D''. Through the back plate extend the rivets or bolts *d*, each 40 of which has a projecting head, *e*, on the inside of the back plate. These rivets or bolts are arranged between the handle-rib C and the side edges of the back plate, as shown in the drawings.

The sections D D' D'' are designed to carry 45 respectively combs, brushes, or cards, and the back plate may be arranged with sections carrying either or any of these devices, as may be desired, the sections being removable. Each section is provided, near the ends of its body- 50 plate or back, with elongated tapering or key

slots *s*, which extend in the direction of its length, and are designed to receive and engage with the heads *e* of the rivets or bolts *d*, above referred to. This engagement is effected by passing the wide ends of said slots over the 55 heads mentioned, and then moving the sections longitudinally until the heads become secured in said slots. The sections are then fastened by turning the thumb-screws E until their ends extend through the center holes, *c*, of said sections, so that they become firmly secured in place with relation to the back plate.

In order to insure coincidence of position between the center holes, *c*, of the sections and the thumb-screws E when said sections, which 65 are reversible, are moved lengthwise in either direction on the heads *e*, it is designed to form the wide end of one key-slot *s* about half an inch from one end of the section, and the wide end of the other slot about an inch from the 70 other end thereof, said slots being in practice about half an inch in length.

Sometimes, instead of using tapering slots and fixed rivet-heads, we may employ ordinary parallel-sided slots and screw-bolts with cross-heads and thumb-nuts, the object being to make the sections removable and reversible, as hereinbefore described.

What we claim, and desire to secure by Letters Patent, is—

1. The combination, with a curry-comb back plate having the headed rivets or bolts *d*, of the sections D D' D'', having the key-slots *s* and center holes, *c*, and the thumb-screws E, passing through said back plate, substantially 85 as specified.

2. The curry-comb consisting of the back plate, A, carrying the inside heads, *e*, the handle-rib C, having the threaded perforations *b*, the thumb-screws E, and the reversible and removable sections having the elongated slots *s* and center holes, *c*, as specified.

In testimony that we claim the above we have hereunto subscribed our names in the presence of two witnesses.

DAVID B. WEAVER.
EPHRAIM R. HOLSINGER.
